UNITED STATES PATENT OFFICE

145,874

DESIGN FOR A TIE RACK

Leonard J. Pauly, Chicago, Ill.

Application March 15, 1946, Serial No. 127,549

Term of patent 7 years

(Cl. D33—8)

To all whom it may concern:

Be it known that I, Leonard J. Pauly, a citizen of the United States, residing at Chicago, in the county of Cook and State of Illinois, have invented a new, original, and ornamental Design for Tie Rack, of which the following is a specification reference being had to the accompanying drawing, forming a part thereof, in which:

Figure 1 is a top plan view of a tie rack embodying my design;

Figure 2 is a front elevation;
Figure 3 is a perspective; and
Figure 4 is a perspective with the parts opened up.

I claim:

The ornamental design for a tie rack, as shown.

LEONARD J. PAULY.
